[57] **ABSTRACT**

A high-voltage electric power converter comprises a plurality of electric valves interconnected in a bridge configuration. In operation the valves are cyclically fired in a predetermined normal sequence by a series of relatively short gate pulses respectively applied thereto. For successful starting, the controls are arranged (1) to idle until the concurrence of a starting command and a proper instant of time for firing any one of said valves, and then (2) to apply simultaneously a gate pulse to that one valve and a gate pulse to the immediately preceding valve in said normal sequence. The controls are preconditioned so that the initial firing angle is within certain limits that ensure continuous conduction by the preceding valve at least from the starting instant to the time at which the succeeding valve is fired.

STARTING CONTROL SCHEME FOR RECTIFIER-INVERTER SYSTEMS

This application is a continuation-in-part of my original U.S. Pat. application Ser. No. 754,921 filed on Aug. 23, 1968.

This invention generally relates to electric power conversion systems and more specifically it relates to control means for starting a static converter in such a system.

There is a growing interest throughout the world in the bulk transmission of electric power by means of high-voltage direct current transmission lines. Opposite ends of such a line are connected to two separate AC electric power systems via a pair of converters. One of these converters functions as a rectifier and the other as an inverter, and by controlling which converter operates as a rectifier and which operates as an inverter, the direction of power flow can be controlled inasmuch as the direction of power flow is from the rectifier terminal over the DC link to the inverter terminal.

A converter comprises the combination of a polyphase power transformer and a plurality of interconnected electric current conducting valves. Each valve can be a mercury arc tube, or a plurality of semiconductor cells such as thyristors that are operated in unison. Typically the valves are arranged in a three-phase, double-way bridge configuration having three separate AC terminals and positive and negative DC terminals. Each bridge contains six valves, and by sequentially applying turn-on (gate) pulses to the respective valves in the proper order and in timed relation to the alternating voltages of the three-phase electric power system to which the AC terminals of the bridge are connected, the flow of power between the AC and the DC terminals is controlled as desired. To form a 12-pulse converter, the DC terminals of two such bridges are connected in series and the transformer windings associated with the AC terminals of the respective bridges are phase-displaced by an electrical angle of 38°.

The time at which a valve is fired, measured in electrical degrees from the cyclically recurring instant that its anode voltage first becomes positive with respect to cathode, is known as the firing angle. As the firing angle is increased from zero, the average magnitude of the rectified voltage between the positive and negative DC terminals decreases from its maximum positive level. As the firing angle approaches 90°, the average DC voltage reverses polarity and a converter will commence to operate as an inverter, whereby power can be transmitted from the DC to the AC terminals.

In the normal steady-state operation of rectifier or inverter bridges, the six valves of a bridge are cyclically fired at intervals of 60 electrical degrees in a predetermined sequence. When fired, each will conduct continuously for approximately 120° at which time the current is transferred to a succeeding valve in the sequence. Thus, at least two valves are always conducting, and current through the bridge can be continuous. In a rectifier-inverter system there need be no particular steady-state phase relationship or synchronism between the firing of the valves in one converter and in the other. At the instant of starting, however, no line current exists to be transferred from one valve to another, and it is necessary to fire two valves simultaneously. Furthermore, to start a rectifier and inverter system, it may be necessary to simultaneously fire two valves of the rectifier bridge and two valves of the inverter bridge, whereby the starting operations of the rectifier and inverter must be synchronized.

Prior art systems have solved the starting problem by applying long gate pulses of 120° duration to the valves. Thus, a firing signal is present for the entire conducting period of the valve so that the rectifier and inverter can be started at any instant without any need for synchronization. It is desirable, however, to use short gate pulses if possible inasmuch as this minimizes the control power required and improves the efficiency of the system while lowering its cost.

SUMMARY OF THE INVENTION

It is an object of this invention to provide an electric power converter starting circuit for a firing system consuming a minimum amount of power.

It is a more specific object of this invention to provide a static power converter starting circuit using short duration gate pulses.

It is another object of this invention to provide for smooth transition between starting and steady-state conditions in a converter using short duration gate pulses.

It is another object of this invention to provide a starting control circuit for a high-power converter that conducts an initially low value of current.

15 Briefly, according to one embodiment of the invention, the converter controls include first means for cyclically generating a family of six 120° signals for effecting turn-on of the converter valves in a predetermined regular sequence. The controls also include six valve-firing means respectively operative

20 when activated to apply relatively short gate pulses to each of the valves in turn, and normally these means are respectively activated in response to the existence of corresponding control signals generated by said first means. However, I provide blocking means for initially preventing activation of any of the

25 valve-firing means until disabled by the coincidence of a starting or recycling command and the leading edge of one of the control signals. For coordinating the starting of the local converter with the starting of another converter connected thereto by a common DC link, the aforesaid disabling action is additionally predicated on the coincidence of the leading edge of any one of six similar control signals generated by the controls associated with the other converter. In either case, to ensure successful starting I provide means for preconditioning the local controls to establish an initial firing angle within

30 predetermined limits (e.g., 60° maximum for a rectifying converter).

35

DETAILED DESCRIPTION

40 The subject matter which is regarded as the invention is particularly pointed out and distinctly claimed in the concluding portion of this specification. The invention, both as to organization and the method of operation, together with further objects and advantages thereof, may be understood by reference to the following description taken in connection with the accompanying drawings in which:

45 FIG. 1 is a schematic circuit diagram of a portion of an HVDC electric power transmission system;

50 FIG. 2 is a series of time charts showing the interrelationships between various voltages and control signals;

55 FIG. 3 is a block diagram of a converter control scheme incorporating the starting control circuit of this invention;

FIG. 4 is a detailed circuit diagram of the terminal starting control of FIG. 3;

FIG. 5 is a detailed circuit diagram of the system starting control of FIG. 3;

FIG. 6 is a detailed circuit diagram of an alternate embodiment of a system starting control;

FIG. 7 is a detailed circuit diagram of a second alternative embodiment of a system starting control;

FIG. 8 is a detailed circuit diagram of the starting bias circuit of FIG. 3; and

FIG. 8A is a schematic diagram of certain modifications in the circuit of FIG. 8.

FIG. 1 shows a typical high-voltage direct current (HVDC) power system in which a DC link comprising normally positive line 7 and relatively negative line 8 is connected at either end through converters 9 and 10 to separate polyphase AC systems at remote terminals (North and South). Each converter comprises N controlled valves arranged in at least one three-phase, double-way bridge configuration having three AC terminals A, B, C which are connected to polyphase conductors (not shown) by means of the set 11 of Y-transformer windings whose voltages alternate at f hertz in the phase rotation.

tion indicated. For purposes of illustration, f will be assumed equal to 60, and N is shown as 6. The six valves, numbered 1 through 6, are fired (turned on) once each cycle in numerical sequence. By controlling the firing angle of the gating pulses applied to these valves, a converter can be made to operate as either a rectifier or as an inverter. One converter in a system will be operated as a rectifier and one converter will be operated as an inverter, and the direction of power flow will be from the rectifier terminal (North) over the DC link to the inverter terminal (South).

In the normal steady-state operation of rectifier or inverter bridges, the six valves of the bridge commence conducting at 60° intervals in their numbered order and continue to conduct for 120° at which time the valve current is transferred (commutated) to another valve. Thus current out of the bridge into a reactive load can be continuous, and in a rectifier-inverter system as shown in FIG. 1, there need be no particular steady-state phase relationship or synchronism between the firing of the valves at opposite terminals. However, at the instant of cold starting, no line current exists to be transferred from one valve to another, so it is necessary to turn on two consecutive numbered valves in the rectifier bridge at the same time. Unless DC line charging current is expected, it may also be desirable simultaneously to fire two valves in the inverter bridge in order to establish a continuous path through which current can build up. A typical path through valves 1 and 2 at each terminal is indicated by the arrows in FIG. 1. If the valves were gated with short pulses in a normal staggered or sequential manner, there would be no path for current when the first valve is fired, and it would revert to the blocking state when the gate pulse ceased. Then there would likewise be no path for current when the second valve is fired 60° later, and starting could not be accomplished. If the gate pulse for valve 1 persists for 60° or longer, starting can easily occur when valve 2 is subsequently fired. The starting method to be described hereinafter, however, can be used to start a static power conversion system when the duration of the gate pulses to the converter valves is shorter than 60° . In one embodiment of the present system the gate pulse duration was selected to be $2\frac{1}{2}^\circ$, and still shorter pulses are contemplated for future systems.

A requirement for successful start up is that the starting instant occur at a time when there are positive anode voltages on all valves simultaneously gated. Before starting, the three valves 1, 3, 5 with common cathode connection constitute a high-impedance balanced Y-load on the balanced Y-source 11. Similar conditions exist for the three valves 2, 4, 6 with common anode connection. Consequently, the voltage across each valve before starting is essentially the line-to-neutral voltage as is represented in graph A of FIG. 2 for valves 1 and 2. After starting, the common-cathode connection (or plus side 7 of the DC link) is always connected to one of the three AC terminals through a conducting valve, and again similar conditions exist for the common anode connection. Therefore, a nonconducting valve under operating conditions is subjected to a line-to-line voltage which is higher in amplitude and 30° lagging in phase compared to the sine waves shown in FIG. 2A. These phase and amplitude differences between valve voltage before and after starting must be accommodated in order to ensure a successful starting operation.

Another requirement for successful starting is that the current remain continuous from one valve firing to the next, which is 60° . This may be no problem if the load is sufficiently inductive, but the firing angle should be limited to less than 60° for purely resistive loads. From graph A in FIG. 2 it can be observed that if starting were attempted by simultaneously firing valves 1 and 2 at the instant "X" corresponding to a steady-state delay angle exceeding 60° for valve 2 but 120° for valve 1, the valve 1 current (resistive load assumed) would fall to zero in less than 60° thereafter and would thus be extinguished before the firing of valve 3, thereby breaking continuity of the current path and making it impossible to start.

For sequentially firing the six valves of a bridge at approximately 60° intervals, a corresponding set of control pulses is

cyclically generated, and to control the converter the timing of the whole family of control pulses as a group is shifted relative to the AC line-to-line voltages. From the sketch of the before-starting valve voltages in graph A it is apparent that any firing angle between 0° and 60° (operating basis) for any valve meets the requirement for positive voltage across both that valve and the preceding valve in the sequence and also ensures that conduction by the latter will not stop before the next valve is fired. However, it is desirable to retard the firing as much as possible, consistent with the other requirements, in order to limit the initial buildup of DC current which may overshoot its normal value before steady-state operation is achieved, and therefore an initial firing angle α of 50° was selected. While this angle is acceptable for starting either a 6-pulse converter or a 12-pulse converter, it will be recognized by persons skilled in the art that in order simultaneously to start all of the bridges of a 24-pulse converter an even shorter delay angle (45° maximum) is dictated by the requirement of positive anode voltages on both of the initially fired valves in each bridge.

FIG. 3 is a block diagram of a converter control scheme which diagram shows converter starting controls for the North terminal of the FIG. 1 system and also shows controls which can be used for coordinated starting of the entire system. For clarity, means for controlling only one bridge is shown although it is to be understood that similar controls will ordinarily be provided for all of the bridges in each converter at each terminal of the electric power transmission system. In FIG. 3, signals representative of the actual converter response and the desired converter response or power order are fed into summing point 13. The output of the summing point is the error between the desired converter response and the actual measured response and is fed into regulator amplifier 14. The DC output signal of amplifier 14 is passed through starting bias circuit 15 to a firing time computer 19 which is also governed by "other limits" as desired. The computer 19 additionally receives signals indicative of the AC system voltages. It responds to these various inputs by generating, at a frequency that is a multiple of f , a train of discrete pulses which are converted by an appropriate distributor 20 into a family of six control signals at the respective points 21 through 26 shown in FIG. 3. These control signals are respectively adapted to effect cyclic firing of the six valves 1 through 6 of the local converter in numerical sequence. As is clearly shown in FIG. 2B, the control signals commence at intervals of approximately 60° , and each subsists for one-third of a cycle (i.e., 120°) which is appreciably longer than $1Nf$ second. The delay angle (α) relating the leading edge of each control signal to the positive-going zero crossing of the anode voltage of the corresponding valve is normally determined by the magnitude of the error signal that is fed to the firing-time computer 19.

The control-signal points 21-26 are shown connected to firing-signal logic means 27 comprising a gate 28 and appropriate logic circuits which enable additional supervision to be exercised over the timing and the order of the firing signals by other permissive and inhibit signals such as those applied to inputs 29 and 30, respectively, as desired. The outputs of the logic circuits are fed to the valve-firing system which includes N (six) blocks 31 through 36 representing means respectively operative when activated to transmit relatively short turn-on or gate pulses to each of the corresponding valves 1-6 in turn. The gate pulses may be in any suitable form, such as electric current or radiant energy (e.g., light). Activation of each of the blocks 31-36 is achieved in response to the existence of the corresponding control signal when permitted by the gate 28 and associated logic.

The design details of the components 19, 20, 27, and 31-36, shown only in block form in FIG. 3, can be conventional and therefore will not be elaborated herein. While the gate 28 has been shown symbolically as an initially open multipole switch, persons skilled in the art will recognize that its function can be accomplished in many different ways, such as providing a normally deenergized input bus to AND-logic circuits, or a nor-

mally energized clamp that blocks or suppresses activation of a bank of transistors. In accordance with the present invention, the gate 28 is initially operative to prevent activation of the valve-firing system and is subsequently disabled only under conditions ensuring that the unblocking action will occur at a particular instant relative to the valve voltages and that the firing angle at this instant is of the proper value. Until unblocked, the controls idle in which state the timing of the control signals at 21-26 is determinable but no gate pulses are actually applied to the valves. For precise control of the unblocking instant, the gate preferably comprises a normally conducting solid-state switch 28' which inhibits the activation of any of the means 31-36 in a manner more fully described below. This switch is turned off, thereby disabling the gate and permitting the valve-firing system to start the converter, at the first appropriate instant after a start switch 40 is actuated in response to receipt at 41 of a starting or recycling command. Graph D of FIG. 2 illustrates the starting signal produced by the switch 40 when operated shortly after the control signal for valve 1 commenced, but the unblocking action is not allowed to occur before the leading edge of the next control signal appears.

To establish the correct instant for unblocking, pulse-mixing means 42 is provided for the deriving short pulses or spikes from the leading edge of the respective control signals which are supplied to it from the distributor 20 through points 21-26. The train of mixed pulses thus produced has been illustrated in graph C1 of FIG. 2. Each of the C1 pulses indicates that a gate pulse is then due for one of the local valves 1-6. It may be desirable in some systems to stretch the mixed pulses into rectangular signals of particular width as shown in graph C2 of FIG. 2, and the mixer 42 is additionally designed to serve this purpose. The formed pulses appear at the output terminal 43 of the mixer 42, and they are fed into a coincidence detector 44 along with a similar train of pulses (shown in graph C3 of FIG. 2 received at terminal 121 from the other converter at the remote end of the HVDC system. The coincidence detector 44 is designed to provide an output only during the time when pulses from both terminals 43 and 121 are in simultaneous existence. See graph C4 of FIG. 2. Where it is acceptable to start the local converter independently of the remote converter, the detector 44 can be omitted or the terminals 43 and 121 can be effectively interconnected, and selected pulses in the train generated by the firing-time computer 19 can be used to energize terminal 43 if desired thereby eliminating the pulse mixer 42.

The output from the coincidence detector 44 is connected to a switch driver 45 which drives via terminal 174 the blocking switch 28'. Switch driver 45 can also be used to simultaneously actuate a similar blocking switch, via terminal 173, in the starting controls for one or more additional converters, thereby starting the other converters. As will soon be described in conjunction with FIG. 5, operation of the switch driver 45, and hence disabling of the gate 28, requires the coincidence of a starting command 41 (start switch 40 operated) and an output of the coincidence detector 44, if used (signalling the beginning of a control signal at one of the points 21-26). In the illustration depicted in FIG. 2, the start switch was operated after the first control signal commenced but before the leading edge of the second control signal, and unblocking occurred in response to the latter event. Since each of the six control signals subsists for appreciably longer than one-sixth cycle, the preceding signal 21 in the normal sequence has not expired when the next signal 22 begins, and the coexistence of two control signals is now assured. Therefore at this particular instant, as is clearly shown in graph E of FIG. 2, the logic means 27 will pass energizing pulses to two consecutively numbered components (e.g., 31 and 32) of the valve-firing system which are immediately activated thereby to transmit short turn-on pulses simultaneously to two valves (e.g., 1 and 2) that are normally fired in succession (see FIG. 2F).

When cold starting an HVDC system such as described herein, the DC power level is initially zero, and assuming the power order is suitably programmed the regulator amplifier 14 will call for the converter output to increase as rapidly as permitted by built-in limits. For successful operation of a bridge under these conditions, I employ bias means 15 for preconditioning the firing angle computer 19 so as to override other inputs and to establish an initial firing angle that meets the previously explained criteria of ensuring positive anode voltage on each of the two valves first fired and of avoiding premature extinction of either of these valves before current is commutated to the valve that is next fired in the normal operating sequence.

Preferably the starting bias circuit 15 comprises means for temporarily superimposing a DC voltage level on the output of the regulator amplifier 14. Various arrangements are possible, but as is schematically shown in FIG. 3 a bias voltage is taken from a variable resistor 16 paralleling a suitable DC source 17 and is applied through a solid-state switch 46 across a resistor 18 which is connected between the amplifier 14 and the firing-time computer 19. The variable resistor 16 controls the magnitude of bias voltage, and appropriate means including the switch driver 45 is provided to control the conduction of solid-state switch 46. In response to the local converter being started, a switch-opening signal is sent by the switch driver 45 to the solid-state switch 46 so that the starting bias is removed. The disabling process of the starting bias circuit will be more fully explained in conjunction with FIG. 8. Thereafter in a normal manner the firing angle of the control signals will depend on the error between the desired converter output and the actual converter output.

To assist in preadjusting the timing of the control signals prior to starting, the prospective firing angle of one of the control signals (e.g., the first one) can be measured by means of a firing-angle monitor 47 supplied from point 21 and from the AC voltage monitors. The firing angle monitor 47 may be merely an oscilloscope or other suitable display. Then with the starting bias circuit 15 in operation and the controls idling, the variable resistor 16 can be adjusted until a firing angle within desired limits is obtained at the local terminal before operating the start switch 40.

FIGS. 2 and 3 show schematically controls that are useful to start a converter at one terminal (North) of an HVDC transmission system in cooperation with concurrent starting of a remote converter at another terminal (South). Persons skilled in the art will recognize that the two pulse trains C2 and C3 respectively applied to the input terminals 43 and 121 of the coincidence detector 44 have been shown in FIG. 2 after appropriate phase shifts to accommodate for any predictable time delays in the communication channel that interconnects the converters which may be separated by long distances. The required coincidence between a pulse in train C2 and a pulse in train C3 will always be obtained if the frequencies of oscillation of the firing time computers associated with the respective converters are not precisely the same. The tendency for these pulses to "beat" can be the result of interconnecting two AC systems of inherently different frequencies f and f' , or it can be artificially imposed, if necessary, by scanning the firing angle of one of the converters within prescribed limits. As has already been noted, a single converter can be independently started by using the same basic scheme with certain simplifying modifications.

FIG. 4 is a detailed circuit diagram of the pulse mixing and forming means 42 shown in block form in FIG. 3. In FIG. 4 a DC power supply (not shown) is connected between terminals 56 and 57, and an intermediate terminal 58 is held at zero volts by being connected to ground.

The control signals supplied to the mixer 42 from the respective points 21-26 are negative-going potentials which abruptly commence when, as is illustrated in particular for point 21, a normally conducting transistor (59) associated with that point in the distributor 20 is turned off. Each of the six control signals are coupled into the pulse mixer through a

separate capacitor 102 and an isolating diode 103 to the base 104 of a common transistor 105. Two transistors 105 and 106 comprise a monostable multivibrator for which resistors 109, 110, 111, 112, 113, and 107, diodes 103 and 116, and a zener diode 108 form a biasing network. Transistor 105 is normally conducting. However, when the leading edge of any one of the negative control signals arrives at its base 104 it ceases to conduct and turns "off," and a positive pulse appears at its collector 114. Transistor 105 remains off for only a certain length of time determined by an RC time constant and then reverts to the conducting state. The RC time constant, which is determined by the values of a rheostat 113 and a capacitor 115, is preferably selected so that the transistor 105 remains off for no longer than 10 electrical degrees. Capacitor 115 is charged by conduction of transistor 106 which is turned on when transistor 105 turns off. Current from transistor 106 charges capacitor 115 to a voltage sufficient to turn on transistor 105 once again, which turns off transistor 106 again.

The above-described operation is repeated every time there is a negative-going control signal at any one of the six inputs 21-26 from the distributor 20. Each of these input signals is connected to the base 104 of the transistor 105 through a capacitor 102 and a diode 103. The pulses present at the base 104 of transistor 105 have been illustrated with inverted polarity in graph C1 of FIG. 2, and the 10° pulses present at the collector 114 of transistor 105 are shown in graph C2. These latter pulses are connected through terminal 43 and conductor 118 to coincidence detector 44. If desired, a similar monostable multivibrator circuit (not shown) located at a remote terminal of the HVDC transmission system provides a second train of pulses C3 at terminal 121 which is coupled through conductor 120 to the coincidence detector 44. To prevent spurious signals or noise interference, conductors 118 and 120 are shielded and the shields are connected through capacitors 119 to ground 58.

As explained before in connection with FIG. 3, coincidence detector 44 provides an output C4 only during the time when pulses at its respective input terminals 43 and 121 are in simultaneous existence. The output from the coincidence detector 44 is connected to the switch driver 45 which drives the blocking switch 28' when the first coincidence pulse C4 appears after the start switch 40 is operated. This will always happen within 10° following the leading edge of one of the control signals at points 21-26.

In the switch driver 45 a conductor 122 is normally at ground potential. This conductor leads to the output terminal 174 which is externally connected through a resistor 125 to the base 126 of a normally conducting transistor 127 comprising the blocking switch 28'. As can be seen in FIG. 4, a resistor 128 serves to furnish biasing for transistor 127 so as to cause it to be normally turned on in which state it maintains the "-blocking bus" 28 at the potential of the positive power supply terminal 56. The firing signal logic means 27 is arranged to prevent the valve-firing system 31-36 from being activated in response to the existence of any of the control signals at points 21-26 so long as the blocking bus 28 is clamped to terminal 56. However, this clamp is disabled and the logic means 27 is unblocked in response to the transistor 127 being driven off by the application to its base of a positive-going output signal from the switch driver 45.

Switch driver 45 also provides another output signal for starting a second converter if desired. This leads to the output terminal 173 which in turn can be connected to blocking switches (not shown) associated with the starting controls of other converters. To prevent disturbances and noise interference, the conductors 122 and 123 are shielded and the shields are connected through capacitors 129 to ground 58.

The output terminal 174 of the switch driver 45 is also coupled through a capacitor 50 to a pulse transformer 51. A secondary winding of the pulse transformer 51 is connected via a shielded conductor 52 to the starting bias circuit, and a signal induced in this winding serves to release the starting bias by initiating opening of the solid-state switch 46 shown

symbolically in FIG. 3. To prevent spurious signals and noise, conductor 52 has its shielding connected through capacitor 53 to ground.

FIG. 5 shows details of the coincidence detector 44 used in one particular embodiment of the invention. The coincidence detector 44 comprises a circuit arrangement for performing a "NAND" logic function. In the absence of positive pulses at both of the input terminals 43 and 121 from the associated pulse forming circuits, the base 130 of a transistor 131 is clamped to ground through diodes 132 and 133 so that the output potential at collector 134 of this normally off transistor is essentially the same as that of the positive power supply bus 56'. Resistors 135, 136, 137, and 138, and capacitor 139 and diode 140 constitute a biasing arrangement for transistor 131. An input signal at only one of the terminals 43 or 121 does not change this situation since the base 130 remains grounded through a parallel path. However, when both inputs simultaneously exist, both input diodes 132 and 133 are back biased and the transistor 131 is forward biased into conduction. Thus, a negative-going output pulse is created at collector 134 of transistor 131 for the duration of coincidence of the two inputs.

The negative coincidence output pulses at the collector 134 of transistor 131 are coupled through a capacitor 141 and a diode 142 to a transistor 143 in the switch driver 45 which as is clearly shown in FIG. 5, preferably comprises a flip-flop circuit. Transistor 143 is immediately turned off in response to such a pulse. Ordinarily, turning off of one side of a flip-flop (transistor) 143 would by reason of the collector 144 of transistor 143 being coupled through resistor 145 and capacitor 146 to the base 147 of a companion transistor 148, cause the transistor which is the opposite side of the flip-flop to turn on. However, this flip-flop is unconventional in that transistor 148 is normally prevented from turning on by supplying forward current through a base-to-emitter diode 149 connected so as to negatively bias the base. The magnitude of this bias current, as determined by a pair of resistors 150 and 151 connected between the cathode of diode 149 and the negative power supply bus 57', is set so that the transient current from the positive DC supply bus 56' through resistor 153 at the input side of transistor 148 will not exceed the bias current, and therefore transistor 148 remains off despite the positive pulses received at its base 147 as a consequence of the turning off of transistor 143. Transistor 143 returns to the conducting state in between successive pulses from transistor 131.

A start switch shown symbolically at 40 is connected through resistor 154 across capacitors 156 and 156. When the start switch 40 is closed by a starting or recycling command, the negative potential at the junction of resistors 150, 151 is reduced to nearly ground level, thereby removing the negative bias on base 147 of transistor 148. Removal of this bias does not itself cause transistor 148 to turn on if transistor 143 is then conducting, since a positive signal is required at base 147 to turn transistor 148 on. However, after the negative bias is removed, transistor 148 is turned on at the next instance of transistor 143 turning off due to a negative input pulse from the coincidence detector 44. Capacitors 155 and 156 provide some degree of filtering across switch 40 in order to prevent premature operation due to positive noise picked up if switch 40 is remotely located. Resistors 150 and 158 provide biasing for transistor 148. Resistor 159 and parallel capacitor 160 are connected between the collector 161 of the transistor 148 and the base 162 of the transistor 143 so that when transistor 148 does turn on a negative bias is imposed on the base 162 of transistor 143 to prevent its return to a conducting state, thus sealing in the flip-flop until subsequently reset by opening the switch 40 to terminate the starting signal.

Before starting, transistor 148 is off so that the potential at its collector 161 is high. Then current is provided through resistor 163 to a DC current amplifier comprising normally conducting transistors 164 and 165 and also through resistor 166 to a duplicate DC current amplifier comprising normally conducting transistors 167 and 168. Resistors 169, 170, 171, and

172 furnish biasing for the two amplifiers. These amplifiers produce positive-going outputs at the respective terminals 173 and 174 when the transistors 168 and 165 are turned off. In operation, transistors 164, 165, 167, and 168 are all turned off when the transistor 148 turns on. The output terminals 173 and 174 are coupled to external circuits as shown in FIG. 4 and previously described.

FIG. 6 shows a simplified alternative embodiment of a portion of the system and converter starting controls in which the blocking switch driver and the starting flip-flop have been omitted. In FIG. 6, the pulse-forming and coincidence detector circuits are substantially the same as in FIGS. 4 and 5, and circuit elements identified in FIG. 6 by primed reference numerals correspond to their unprimed counterparts in FIGS. 4 and 5. Therefore, reference may be had to the preceding discussion for a description of the operation of these circuit elements.

In FIG. 6 the start switch 181 is symbolically illustrated as a two-pole normally closed switch. Before starting and with the contacts of switch 181 closed, a thyristor blocking switch 182 is maintained in a blocked condition (conducting) due to positive current at its gate 183 regardless of whether or not the parallel commuting transistor 184 is turned on as a result of coincidence output pulses received from the collector 134' of transistor 131'. When the start switch 181 is operated (opened) on command, the thyristor control circuit, including resistors 185 and 186 and capacitor 187, is deenergized and the gate drive for the thyristor blocking switch 182 is removed, but latching action keeps this switch conducting. When, however, there is a negative-going coincidence output pulse from the normally off transistor 131' whose collector 134' is coupled through resistor 189 to the base 188 of transistor 184, transistor 184 momentarily turns on. Now the voltage drop across transistor 184 becomes less than the voltage drop across thyristor blocking switch 182, and the thyristor 182 is commutated off. On the expiration of the coincidence output pulse the transistor 184 immediately reverts to its nonconducting state and the potential of blocking bus 28 is lowered, thereby disabling its blocking function and enabling the firing signal logic means 27 to energize the valve firing system 31-36 in response to the existence of corresponding control signals at points 21-26. Inasmuch as power for the pulse forming circuit comprising transistors 105' and 106' is, in this embodiment, derived through a resistor 190 from the blocking bus 28, the fall of positive potential of the blocking bus so reduces the amplitude of pulses created by the pulse forming circuit that the transistor 131' in the coincidence detector will now remain continuously off, whereby the starting controls are sealed in until subsequently reset by closing the start switch 181 to trigger the thyristor 182. Without a seal in provision, the coincidence pulses could periodically turn on transistor 184 and thereby upset the normal steady-state operation of the converter. In FIG. 6 the labeled interconnections with the South terminal are, as previously explained, optional.

FIG. 7 shows still another embodiment of the system starting control in which the starting flip-flop and switch driver of FIG. 5 are replaced by a silicon-controlled switch 191 used to drive through its anode gate 192 the transistor 127 comprising blocking switch 28'. Circuit elements identified in FIG. 7 by double primes are similar to corresponding elements in FIGS. 4 and 5 referred to by unprimed numbers. A start switch 193 is normally closed so that silicon-controlled switch 191 is normally biased on by means of resistors 194, 195, and 196 and capacitor 197. Since silicon-controlled switch 191 is on, current is conducted through its anode gate 192 so that transistor 127 is also conducting. When the start switch 193 is opened on command, there is no immediate change. However, as soon as simultaneous pulses are received from the pulse forming circuits of both terminals 43 and 121, so that both of the diodes 132'' and 133'' are reverse-biased, transistor 131'' turns on, commuting off silicon-controlled switch 192. When silicon-controlled switch 192 turns off conduction

through its anode gate ceases, and transistor 127 is turned off, which unclamps the blocking bus 28 and allows activation of the valve-firing system 31-36 under control of the family of relatively long control signals generated at points 21-26. The silicon-controlled switch 192 is so biased that it does not again turn on so long as the start switch 193 remains open.

FIG. 8 is a detailed circuit diagram of a useful embodiment of the starting bias circuit 15 illustrated schematically in FIG. 3. In FIG. 8 a silicon-controlled switch 198 has its anode gate 199 connected through resistors 200 and 201, diodes 202 and 203, and resistor 204 to the base 205 of a transistor 206. When the silicon-controlled switch 198 is on, conduction occurs through its anode gate 199 so that transistor 206 is turned on an amount determined by the adjustment of resistor 201. When transistor 206 is on, a cascaded transistor 207 is also conducting. Transistor 207 conducts current from a DC power supply 17p, 17n through a diode 209, a bias polarity switch 210, and the resistor 18. The resulting voltage drop across resistor 18 is the starting bias voltage. The magnitude of this voltage, and hence the firing angle that characterizes the gate pulses initially applied to the valves to start the converter, depends on the selection and setting of resistor 201 which functionally corresponds to the potentiometer 16 shown in FIG. 3.

Normally, however, silicon controlled switch 198 is not turned on and its anode gate 199 is not conducting. To turn on the switch 198 in preparation for starting, appropriate means shown symbolically as a normally open switch 211 is momentarily actuated to connect a biasing network comprising resistors 213 and 214 and capacitor 215 across the DC supply terminals 17p and 17n. The resultant voltage appearing at the cathode gate 212 of silicon-controlled switch 198 turns it on so that, as explained before, the transistors 206 and 207 are initially operative to establish a starting bias voltage across resistor 18. It will now be apparent that the parts 198, 206 and 207 shown in FIG. 8 fulfill the function of the solid-state switch 46 previously described.

A forward bias is normally applied across the silicon-controlled switch 198 by means of resistor 216, diode 217 and resistor 218. However, when an actuating signal is received from the starting bias release transformer 131 (shown in FIG. 4) over shielded conductor 132, which conductor is coupled through a capacitor 219 to the resistor 218, a negative pulse is impressed across the resistor 218 to direct anode current from the silicon-controlled switch 198 so as to commutate it off. Thus, current ceases in the anode gate 199, and the transistors 206 and 207 tend to be turned off. However, while transistors 206 and 207 were conducting a capacitor 220 connected between 17p and the junction of diodes 202 and 203 was charged to some voltage, and now discharge of this capacitor through an adjustable resistor 221 and the diode 203 effectively retards the decay of forward bias on the transistors 206 and 207. Thus these transistors will continue to conduct in a progressively diminishing manner for a space of time, and the starting bias voltage originally established across resistor 18 slowly decays. This assures a smooth transition between starting and steady-state operation of the converter at the rectifier terminal of the power conversion system when the starting bias circuit 15 is disabled.

Several adjustable features are provided in the starting bias circuit 15. Bias polarity switch 210, for example, provides for reversing the polarity of the bias voltage appearing across resistor 18. Rheostat 221 provides for adjusting the rate of decay of the starting bias voltage when silicon-controlled switch 198 is "opened" (turned off).

An indicating lamp 222 is connected between the anode gate 199 of silicon-controlled switch 198 and the positive supply voltage terminal 17p via a resistor 224. Zener diode 223 is connected across the indicator lamp 222 to limit the voltage thereacross. The indicator lamp serves to give a visual indication of when silicon-controlled switch 198 is on and, hence, when the firing-time computer is preconditioned for starting.

The invention described above can readily be adapted to control the starting of a 12-pulse converter comprising two six-pulse bridges whose DC terminals are connected in series to the DC link and whose AC terminals are respectively connected to a three-phase AC power system by means of two sets of polyphase transformer windings which are phase displaced 30 electrical degrees with respect to each other. In this context the control components 27, 28', and 31-36 shown in FIG. 3 for one six-pulse bridge would be duplicated for the additional bridge. So long as the distributor 20 provides 120° control signals for the firing signal logic of the respective bridges, and the firing time computer 19 is preconditioned for an initial delay angle no greater than a predetermined amount (e.g., 60°), successful starting can be obtained by having a common switch driver 45 actuate the blocking switches 28' of both bridges simultaneously. In an analogous manner my invention can be used to simultaneously start three bridges in an 18-pulse converter (with a maximum initial firing angle of 50°) or four bridges in a 24-pulse converter (with a maximum initial firing angle of 45°). Alternatively, in cooperation with appropriate bypass switching, the respective bridges of a 12 or more pulse converter can be started seriatim, each in the 6-pulse mode hereinbefore described.

As was previously mentioned, operation of the switch driver 45 can supply, via the output terminal 173, the starting command for another converter, and the blocking switch 28, 28' at the other converter can be arranged to immediately respond to this command. If such a scheme is used in a situation where the distal converter is not coordinated with the local converter by the coincidence detecting function previously described (i.e., coincidence detector input 121 omitted), and where the alternating voltage of the system to which the AC terminals of the distal converter are connected is not synchronized with that of the local AC system, the initial gate pulses for the valves of the distal converter will have a random firing angle which might be unpropitious. Improper firing can nevertheless be avoided by initially preconditioning the firing time computer associated with the distal converter for generating gate pulses characterized by a firing angle which is no greater than the maximum permissible initial firing angle minus $360/N$ degrees, where N is the number of sequentially fired valves forming the converter. Thus in a 12-pulse converter, for example, the firing angle could be preset at 20° which equals the maximum angle 60° minus $360/12$ degrees less a safety margin of 10°.

On receiving its starting command, the blocking switch of the control means for the 12-pulse converter discussed in the preceding paragraph will immediately disable the idle-causing blocking means, whereupon simultaneous gate pulses are generated for and applied to the four valves which, in the normal firing sequence, in turn precede the one valve that is due to be fired by the gate pulse next generated, and successful starting of the converter is obtained. This can be illustrated, by way of example, by assuming that the incidence of a starting command is 15 electrical degrees before the time when the control signal for valve 3 in the leading bridge is due to commence. As soon as this starting command is received, gate pulses for the two preceding valves 2 and 1 in both bridges of the converter are simultaneously released. Since the controls were idling with a firing angle of 20° in this example, the actual firing angle for valve 2 in the lagging bridge is 35° which is less than ideal for minimizing current overshoot but on the safe side for starting. In practice the initial firing angle can have a value anywhere between 20° and 50°, a proper range for starting purposes.

It will be observed that the foregoing "random" mode of operation of my invention is similar in result to the scanning mode previously described. In the scanning mode suitable means is provided initially to precondition the firing time computer for generating control signals whose delay angle varies with time between predetermined maximum and minimum values. If the maximum value were set, for example, at 50° and the minimum at 20° in a 12-pulse converter, the moment of

coincidence of the starting signal and the leading edge of one of the control signals, and hence the initial firing angle, could actually be anywhere in between. Since the initial firing angle is uncertain but within a proper range in either case, it may be preferable to use the "random" mode of operation at the distal converter of the system, thereby eliminating the need for detecting pulse coincidence at opposite ends of the DC link.

When the firing angle of the initial gate pulses is less than the maximum permissible value that would ensure successful starting, the previously mentioned problem of current overshoot in the DC link may be aggravated. Of course after current builds up to a certain level the regulator amplifier 14 will take over and retard the firing angle as required to properly control the steady-state operation of the converter. But due to timelags in its response, the regulator may act too late to correct appreciable initial overshoot. This possibility can be avoided by modifying the starting bias means 15 so that for a short time immediately following operation of the switch driver 45 the firing angle is forced to increase. In other words, the bias means 15 is arranged temporarily to augment its preconditioning effect, thereby causing the firing-time computer to further retard the firing angle of the gate pulses, in response to starting the converter. One way to implement this idea is disclosed in FIG. 8A.

The components and circuits of the modified starting bias means are intended to be the same as shown in FIG. 8 except for those changes and additions specifically indicated in FIG. 8A. The modified version will operate in the manner previously described, in so far as its initial preconditioning effect on the firing time computer is concerned. However, in FIG. 8A operation of the switch driver 45 is used to initiate an augmented preconditioning effect instead of immediately disabling the bias means. This can be accomplished by using the signal from the output terminal 173 of the switch driver to actuate a suitable switch 231 which will connect the capacitor 220, via an isolating diode 232 and a resistor 233, to a different voltage setting of the bias-determining adjustable resistor 201', whereupon the capacitor 220 begins charging, the bias voltage rises, and hence the firing angle progressively increases from the initially established value (e.g., 20°) to a higher preset limit (e.g., 80°).

The above-described firing angle increase (ramp up) occurs over an operating interval of the order of a few milliseconds, for example, which interval is determined by the time constant of the charging circuit for the capacitor 220. Preferably this time constant is selected so that the rate at which the firing angle increases to its higher limit will approximate the rate of rise of current in the DC link. Shortly after the new, higher limit is attained, the starting bias means is disabled. Since the increase in firing angle was accompanied by a reduction in the DC voltage generated by the converters, the DC link current is now changing much less rapidly and is closer to the ordered value when the regulator assumes control of the firing angle. This results in a more orderly starting process than would be obtained if the regulator were allowed to take over control of the firing angle at a time when a large error exists between the ordered current and the actual current.

The modified starting bias means depicted in FIG. 8A is disabled in delayed response to the converter being started. The disabling action is the same as that described in connection with FIG. 8 except that it is initiated by a timer 234 which is coupled through the capacitor 219 to the resistor 218. The timer itself is activated when the converter starts, either by a current-sensing circuit 235 which responds to a threshold magnitude of current in the line 7 of the DC link, or alternatively by a signal conveyed over broken line 236 from the output terminal 173 of the switch driver. The timer 234 can be arranged to delay disabling of the modified bias means for approximately 8 milliseconds, for example.

It should be understood that means other than the modified starting bias circuit that is particularly described above can be used to incrementally adjust the timing of the gate pulses dur-

ing the early stages of the starting process. For example, this function can alternatively be incorporated in the companion circuitry that is provided to impose limits on the firing time computer 19.

While I have shown and described particular embodiments of my invention, it will be obvious to those skilled in the art that various other changes and modifications may be made without departing from my invention in its broader aspects. For example, the same basic starting scheme is applicable to either analog or digital forms of converter controls. If desired, the distributor 20 can be designed to provide control signals of 180° duration instead of 120°, in which event an additional but harmless gate pulse will be applied to a third valve of the bridge at the instant of starting. It has already been pointed out that the invention is useful for starting a converter either independently or in cooperation with at least one other converter at the same or a remote terminal of the HVDC power transmission system. (An individual converter need not be started simultaneously with a remote converter if it is coordinated with appropriate bypass switching, or if the initial current that flows in the DC link is line charging current, or if the remote converter comprises diode bridges.) Coordinated starting of two or more converters can be achieved even though the converters are respectively connected to AC systems of different frequencies or they are formed by different numbers of valves. Accordingly, I intend in the appended claims to cover all such changes and modifications as fall within the true spirit and scope of my invention.

What I claim as new and desire to secure by Letters Patent of the United States is:

1. For starting an electric power converter comprising a plurality of electric current conducting valves connected in a bridge configuration and arranged to commence conducting in a predetermined normal sequence, the combination of:

- a. control means for cyclically generating a succession of relatively short gate pulses for the respective valves of the converter and for applying said pulses to corresponding valves so as to fire the valves in said normal sequence;
- b. said control means including means initially operative to cause said control means to idle, in which state the timing of said gate pulses is determinable but no gate pulses are actually applied to said valves;
- c. means for producing a starting signal; and
- d. disabling means connected to said control means and operative to disable said initially operative means in response to the coincidence of said starting signal being produced and one of said gate pulses being due;
- e. said control means being arranged upon operation of said disabling means to apply said one gate pulse to the corresponding valve and simultaneously to apply a gate pulse to the preceding valve in said normal sequence, thereby starting the converter.

2. For starting an electric power converter comprising a plurality of electric current conducting valves connected in a bridge configuration and arranged to commence conducting in a predetermined normal sequence, the combination of:

- a. control means for cyclically generating a succession of relatively short gate pulses for the respective valves of the converter and for applying said pulses to corresponding valves so as to fire the valves in said normal sequence;
- b. said control means including means initially operative to cause said control means to idle, in which state the timing of said gate pulses is determinable but no gate pulses are actually applied to said valves;
- c. additional means initially operative to precondition said control means for generating gate pulses characterized by a firing angle within predetermined limits;
- d. means for producing a starting signal; and
- e. disabling means connected to said control means and operative in response to said starting signal to disable the initially operative means which is identified in the above paragraph (b) when one of said gate pulses is due;

5 f. said control means being arranged upon operation of said disabling means to apply said one gate pulse to the corresponding valve and simultaneously to apply a gate pulse to the preceding valve in said normal sequence, thereby starting the converter.

3. The combination set forth in claim 2 in which said firing angle is no greater than 60 electrical degrees on an operating basis.

10 4. The combination set forth in claim 2 in which said additional means includes means for disabling the same in response to starting the converter.

15 5. The combination set forth in claim 4 in which said additional means is arranged to progressively change its preconditioning effect in response to starting the converter.

6. The combination set forth in claim 2 in which said additional means includes means for disabling the same in response to operation of the disabling means identified in paragraph (e).

20 7. For starting a first electric power converter comprising a plurality of electric current conducting valves connected in a bridge configuration and arranged to commence conducting in a predetermined normal sequence, which converter is adapted to be used in conjunction with another converter connected thereto via a DC link, the combination of:

30 a. control means for cyclically generating a succession of relatively short gate pulses for the respective valves of said first converter and for applying said pulses to corresponding valves so as to fire the valves in said normal sequence;

b. said control means including means initially operative to cause said control means to idle, in which state the timing of said gate pulses is determinable but no gate pulses are actually applied to said valves;

c. means for producing a starting signal; and

40 d. disabling means connected to said control means and to said starting signal producing means and also adapted to be connected to similar control means associated with said other converter, said disabling means being operative to disable said initially operative means in response to the coincidence of

i. said starting signal,

ii. a gate pulse being due at said first converter, and

iii. a gate pulse being due at said other converter;

45 e. the control means for said first converter being arranged upon operation of said disabling means to apply said one gate pulse to the corresponding valve and simultaneously to apply a gate pulse to the preceding valve in said normal sequence, thereby starting said first converter.

50 8. For starting an electric power converter in response to a starting or recycling command, said converter comprising N electric valves connected in at least one bridge configuration between a DC link and a polyphase system whose voltage alternates at a frequency of f hertz, an improved control circuit comprising:

60 a. first means associated with the converter for cyclically generating a family of N control signals for effecting turn on of the respective valves of that converter in a predetermined sequence, each of said control signals subsisting appreciably longer than $1/Nf$;

b. a valve-firing system comprising N second means respectively operative when activated to transmit relatively short turn-on pulses to each valve in turn;

65 c. third means connected to said first means and to said firing system for respectively activating each of said second means in response to the existence of a corresponding control signal; and

d. blocking means connected to said third means for initially preventing activation of any second means until disabled in response to the coincidence of

i. said command and

ii. the leading edge of one of said control signals.

70 9. The improved control circuit of claim 8 in which said first means is arranged to generate said control signals in timed

relation to the alternating voltage and in which starting bias means is connected to said first means for establishing the initial firing angle of said control signals within predetermined limits.

10. The improved control circuit of claim 9 in which means is provided for disabling said starting bias means in response to said blocking means being disabled.

11. For cold starting an electric power converter comprising 6 electric valves connected in a double-way bridge configuration between a set of polyphase AC conductors and a pair of 10 DC terminals, the combination of:

- a. first means for cyclically generating a set of six control signals for effecting turn on of the respective valves in a predetermined sequence, said control signals commencing at intervals of approximately one-sixth cycle and each subsisting for appreciably longer than one-sixth of a cycle;
- b. starting bias means for preconditioning said first means so that the initial firing angle of said control signals can not exceed 60 electrical degrees;
- c. a valve-firing system comprising six means respectively operative when activated to apply relatively short gate pulses to each valve in turn;
- d. means interconnecting said first means and said valve-firing system for respectively activating each of said six means in response to the existence of a corresponding control signal;
- e. said interconnecting means including blocking means for initially preventing activation of any one of said six means;
- f. means operative while two of said control signals coexist for disabling said blocking means and thereby permitting the converter to start; and
- g. means responsive to the converter starting for disabling said starting bias means.

12. For starting an electric power system comprising at least first and second converters respectively connected to opposite ends of a DC link, the first converter comprising N electric valves connected in at least one bridge configuration between one end of said DC link and polyphase conductors the voltages across which alternate at a frequency of f hertz, and the second converter comprising N' electric valves connected in at least one bridge configuration between the other end of said DC link and polyphase conductors the voltages across which alternate at a frequency of f' hertz, an improved control circuit comprising:

- a. first means associated with each of said converters for cyclically generating a series of control signals for effecting turn on of the respective valves of that converter in a predetermined sequence, the control signals generated by the first means at said first converter subsisting for appreciably longer than $1/Nf$ and the control signals generated by the first means at said second converter subsisting appreciably longer than $1/N'f'$;
- b. second means connected to each of said first means and operative in response to the existence of the control signals respectively generated thereby for sequentially transmitting relatively short turn-on pulses to the respective valves of the associated converter; and
- c. third means at each converter for initially blocking operation of the second means until disabled, said third means including means for disabling the same in response to the coincidence of:
  - i. the coexistence of at least two control signals generated by the first means associated with the first converter and
  - ii. the coexistence of at least two control signals generated by the first means associated with the second converter.

13. For starting an electric power system comprising at least first and second converters respectively connected to opposite ends of a DC link, each converter comprising a plurality of electric valves connected in a bridge configuration, an improved control circuit comprising:

- a. means 19, 20 associated with each of said converters for producing a first set of control signals;
- b. means 42 for deriving a series of short pulses from the control signals of each first set;
- c. means 44, 45 for detecting when individual pulses at both converters are in substantially simultaneous existence; and
- d. means 27, 28', 31-36 responsive to the simultaneous existence of said individual pulses for deriving from said control signals at each converter a set of gate pulses for the valves of the associated converter.

14. A cold starting process for a multivalve, double-way electric power converting bridge including the steps of

- a. cyclically generating a family of staggered, relatively long control signals adapted to activate a valve-firing system for turning on the respective valves of the bridge in a predetermined normal sequence in timed relation to the voltages across the AC terminals of the bridge;
- b. readjusting the timing of said control signals to establish an initial firing angle for said valves within predetermined limits;
- c. detecting the leading edges of successive control signals;
- d. applying one of said control signals to said valve-firing system at an instant of time determined by the detection of its leading edge, thereby turning on a corresponding valve;
- e. simultaneously applying an earlier control signal to said valve-firing system to turn on the valve that precedes said corresponding valve in said normal sequence; and
- f. thereafter applying said control signals in turn to said valve-firing system.

15. The process set forth in claim 14 including an additional step of changing the effect of said readjusting step when the bridge starts.

16. The combination set forth in claim 2 in which said additional means is arranged initially to precondition said control means for generating gate pulses characterized by a firing angle which varies with time between predetermined maximum and minimum values.

17. The combination set forth in claim 2 in which said additional means is temporarily operative in response to starting the converter to cause said control means to generate gate pulses characterized by a progressively increasing firing angle.

18. The combination of claim 7 in which additional means is provided initially to precondition the control means associated with said other converter for generating gate pulses characterized by a firing angle which varies with time between predetermined maximum and minimum values.

19. The improved control circuit of claim 9 in which said starting bias means is arranged temporarily to effect a progressively increasing firing angle in response to said blocking means being disabled.

20. For starting an electric power converter comprising N electric current conducting valves connected in at least one bridge configuration and arranged to commence conducting in a predetermined normal sequence, the combination of:

- a. control means for cyclically generating a succession of relatively short gate pulses for the respective valves of the converter and for applying said pulses to corresponding valves so as to fire the valves in said normal sequence;
- b. said control means including means initially operative to cause said control means to idle, in which state the timing of said gate pulses is determinable but no gate pulses are actually applied to said valves;
- c. additional means initially operative to precondition said control means for generating gate pulses characterized by a firing angle within predetermined limits;
- d. disabling means connected to said control means and operative in immediate response to receipt of a starting command to disable the initially operative means which is identified in the above paragraph (b);
- e. said control means being arranged upon operation of said disabling means to generate and apply simultaneous gate pulses for and to the $N/3$ valves which, in said normal

- sequence, in turn precede the one valve that is due to be fired by the gate pulse next generated after the incidence of said starting command; and
- f. means for supplying said starting command to said disabling means when starting is desired.
21. The combination of claim 20 in which said additional means is arranged initially to precondition said control means for generating gate pulses characterized by a firing angle which is no greater than a predetermined maximum permissible initial firing angle minus $360/N$ degrees.

22. The combination of claim 20 in which said additional means is temporarily operative in response to starting the converter to cause said control means to generate gate pulses characterized by a progressively increasing firing angle.

23. For starting an electric power converter in response to a starting or recycling command, said converter comprising N electric valves connected in at least one bridge configuration between a DC link and a polyphase system whose voltage alternates at a frequency of f hertz, an improved control circuit comprising:

- a. first means associated with the converter for cyclically generating a family of N control signals for effecting turn on of the respective valves of that converter in a predetermined sequence in timed relation to the alternating voltage, each of said control signals subsisting appreciably longer than $1/Nf$;
- b. starting bias means connected to said first means for establishing an initial firing angle of said control signals no greater than a predetermined maximum permissible initial firing angle minus $360/N$ degrees;
- c. a valve-firing system comprising N second means respectively operative when activated to transmit relatively short turn-on pulses to each valve in turn;
- d. third means connected to said first means and to said firing system for respectively activating each of said second means in response to the existence of a corresponding control signal; and
- e. blocking means connected to said third means for initially preventing activation of any second means until disabled in response to said command.

24. For starting an electric power system comprising at least first and second converters respectively connected to opposite ends of a DC link, each converter comprising a plurality of electric valves connected in a bridge configuration, an improved control circuit comprising:

- a. means associated with each of said converters for producing a first set of control signals;
- b. means for deriving a series of short pulses from the control signals of the first set produced at said first converter;
- c. means associated with said first converter and responsive

- to the coexistence of a starting command and one of said short pulses for deriving from the control signals at said first converter a set of gate pulses for the valves of that converter, thereby starting said first converter;
- 5 d. starting bias means associated with said second converter and initially operative to establish a predetermined firing angle of the control signals of the first set produced at said second converter; and
- 10 e. means associated with said second converter and responsive to starting of said first converter for deriving from the control signals at said second converter a set of gate pulses for the valves of the latter converter, thereby starting said second converter.
25. The improved control circuit of claim 24 in which said starting bias means is initially operative to establish a firing angle which is no greater than a predetermined maximum permissible initial firing angle minus the electrical degrees between successive gate pulses for the valves of said second converter.
- 20 26. The improved control circuit of claim 24 in which said starting bias means is arranged temporarily to effect a progressively increasing firing angle of the control signals produced at said second converter in response to starting of said second converter.
27. For starting an electric power converter in response to a starting or recycling command, said converter comprising N electric valves connected in at least one bridge configuration between a DC link and a polyphase system whose voltage alternates at a frequency of f hertz, an improved control circuit comprising:
- 30 a. first means associated with the converter for cyclically generating a family of N control signals for effecting turn on of the respective valves of that converter in a predetermined sequence and at a predetermined firing angle, each of said control signals subsisting appreciably longer than $1/Nf$;
- b. a valve-firing system comprising N second means respectively operative when activated to transmit relatively short turn-on pulses to each valve in turn;
- c. third means connected to said first means and to said firing system for respectively activating each of said second means in response to the existence of a corresponding control signal;
- d. said third means including blocking means for initially preventing activation of any second means until disabled;
- e. means for disabling said blocking means in response to said command, thereby starting the converter; and
- f. bias means connected to said first means for temporarily effecting a progressively increasing firing angle in response to starting the converter.
